UNITED STATES PATENT OFFICE.

JOHN F. MEIGS AND EMIL A. GATHMANN, OF SOUTH BETHLEHEM, PENNSYLVANIA, ASSIGNEES TO BETHLEHEM STEEL COMPANY, OF SOUTH BETHLEHEM, PENNSYLVANIA, A CORPORATION OF PENNSYLVANIA.

MECHANICAL TIME-FUSE.

No. 896,135.

Specification of Letters Patent.

Patented Aug. 18, 1908.

Application filed December 19, 1904. Serial No. 237,562.

To all whom it may concern:

Be it known that we, JOHN F. MEIGS and EMIL A. GATHMANN, citizens of the United States, residing at South Bethlehem, Northampton county, Pennsylvania, have invented 5 certain new and useful Improvements in Mechanical Time-Fuses, of which the following is a specification.

Our invention relates to time fuses for use 10 with projectiles, as in shrapnel or explosive projectiles, and has for its object the timing of the explosion, and consists in the construction and arrangement of parts fully set forth hereinafter in connection, in some instances, 15 with the use of a plastic material for controlling the detent of the exploder.

In the accompanying drawings: Figure 1 is a longitudinal sectional of a fuse embodying 20 our improvement; Fig. 2, a cross section on the line 1—1, Fig. 1; Fig. 3, an external view 25 of the fuse shown in Figs. 1 and 2.

The casing A of the fuse may be suitably 30 constructed in any desired manner having two sections 1, 2, as in the construction of Figs. 1 and 2, the section 1 having a threaded 35 nipple 19, for screwing into a corresponding socket of the projectile, with a magazine chamber 12 having ports or channels a, b.

In a transverse recess or chamber e, is the 30 exploder, which, as shown, consists of a movable hammer 8 and an anvil 22 which has a firing pin 9 adapted to engage the cap 10, the seat of which is in the hammer. The hammer in this case has a chamber 11 for the 35 priming charge and a vent i, and the channel a is arranged to be closed or covered by the hammer when it is in its retracted position, but to be uncovered to permit the passage of the ignited gases to the magazine when the 40 hammer is thrown outward under centrifugal action.

To hold the hammer in its retracted position until the firing of the projectile, there is provided a suitable detent which, as shown, 45 is a pin 7 projecting from a piston 5 which is movable longitudinally in a chamber e of the casing under the action of a spring 6. The detent is maintained in its position holding the hammer, by any suitable locking device, 50 but, as shown, there is a block 14, which may be spherical, lying in an opening n in the wall between the chamber e and a parallel chamber f, and a retaining device 13 in the latter

chamber when in its forward position thrusts the block inward in front of a shoulder 24 of 55 the piston. The retaining device 13 is in the form of a block or plunger having a recess h so arranged that when the retaining device moves backward the recess will be brought opposite the block 14 permitting the latter to 60 move outward and release the piston of the detent when the latter will be projected forward by its spring and the hammer will be released and will move radially outward under 65 centrifugal action, bringing the cap against the pin of the exploder and firing the charge.

Normally the retaining device 13 is in its forward position confined by a shear wire 15, which is cut on the firing of the projectile, owing to the inertia of the said device. In 70 order to prevent any possible movement of the retaining device 13 until a projectile is to be used, a cotter pin 16 is passed through corresponding openings in the casing and retaining device with its head 16^a outside the 75 shell so that the said pin may be withdrawn by hand prior to firing.

Any suitable means may be employed in the construction shown for controlling the outward movement of the detent and for 80 timing this movement so as to time the explosion, but, as shown, the chamber e is filled with a retarding medium consisting of a material which when confined holds the piston in its retracted position, but with a gate or 85 valve of any suitable character which may be opened to permit the flow of the said material from the chamber e into the chamber m in the shell, the adjustment of the gate determining the rapidity of the flow and the 90 time of the explosion. The parts shown may be used in connection with a liquid but to obviate objections to the use of liquid materials we employ a granular material, that is, a material of such a character that it will 95 not be affected by extremes of heat and cold or change its capacity to flow under normal conditions and that will not be liable to leak past the piston as in the use of a liquid. While granular materials of different characters may be made use of, we prefer a material in which the grains are flattened as in what is known as "flake graphite", but talc, fine metallic powders, as bronze powders, or fine mica, may be used, and a lubricant may 100 be combined therewith in some cases.

In the construction shown in Figs. 1 and 2, the valve or gate 26 is in the form of a plate sliding across the end of the chamber and provided with a V-shaped notch 3, the normal position of the gate being shown in Fig. 1, and as this position is transverse to the axis of the casing, the gate can be thrown outward by centrifugal action. Normally the gate is locked in the position shown in Fig. 1 by the retaining device 13, a projection 17 of which occupies a position opposite the edge of the gate until the retaining device is relatively carried rearwardly by its inertia. The extent to which the gate or valve is moved determines the extent of the opening for the escape of the material from the chamber 4, and in order to secure the proper adjustment of the gate to thus control the flow and determine the time of explosion, there is provided any suitable stop device capable of being adjusted to position to limit the extent of movement of the gate or valve from outside the casing. As shown in Figs. 1 and 2, the stop device consists of a disk or plate 18 having an edge p so curved that the turning of the disk 18 to different positions will determine the extent to which the gate may be moved radially before striking said edge. To adjust this stop plate or disk, the latter is connected by pins 29 to the movable section 2 of the casing to turn with the latter, and pawls 20 upon the section 2 are adapted to the teeth 30 in an annular recess 31 of the body 1 of the casing, so as to permit the rotation of the section 2 in the direction of rotation of the projectile only, and to retain the section 2 after adjustment relatively in one direction, it is secured by tightening a clamping ring 32 flanged to overlap a flange on the section 2, having threads engaging corresponding threads of the section 1 and holding the two sections together. The pawls are spring pawls and can yield to permit the rotation of the dome in the direction in which the projectile will rotate.

To time the fuse, the section or dome portion 2 of the casing is turned to bring an indicating mark thereon, Fig. 3, in proper relation to a graduation on the ring 32.

Without limiting ourselves to the precise construction and arrangement of the parts shown, we claim—

1. A time fuse for projectiles provided with exploding means, a detent, and a granular material the flow of which controls the movement of the detent, substantially as set forth.

2. A time fuse for projectiles provided with exploding means, a detent, a granular material the flow of which controls the movement of the detent, and means for confining said material until the projectile is fired, substantially as set forth.

3. A time fuse for projectiles provided with exploding means, a detent, a material

the flow of which controls the movement of the detent, a gate confining the material in place, and means for automatically opening said gate when the projectile is fired, substantially as set forth. 70

4. A time fuse for projectiles provided with an exploder, a detent for the movable part of the exploder, a chamber containing a body of granular material controlling the movement of the detent, and a gate controlling the flow of said material from the chamber, substantially as set forth. 75

5. A time fuse for projectiles provided with an exploder, a detent for the movable part of the exploder, a chamber containing a body of material for controlling the movement of the detent, and a gate controlling the flow of said material from the chamber, said gate arranged to move under centrifugal action, substantially as set forth. 80

6. A time fuse for projectiles provided with an exploder, a detent for the movable part of the exploder, a chamber containing a body of material for controlling the movement of the detent, a gate controlling the flow of said material from the chamber, said gate being arranged to move radially to release the material, and a retaining device for holding the gate closed, substantially as set forth. 85

7. A time fuse for projectiles provided with an exploder, a detent for the movable part of the exploder, a chamber containing a body of material controlling the movement of the detent, a gate controlling the flow of said material from the chamber, said gate arranged to move radially under centrifugal action, and a retaining device for holding the gate closed, said device arranged to shift its position on firing the projectile, substantially as set forth. 95

8. A time fuse for projectiles provided with an exploder, a detent for the movable part of the exploder, a chamber containing a body of material controlling the movement of the detent, a gate controlling the flow of said material from the chamber, said gate arranged to move radially under centrifugal action, a retaining device for holding the gate closed, said device arranged to shift its position on firing the projectile, and a retainer for said retaining device, substantially as set forth. 100

9. A time fuse for projectiles having exploding means, a detent therefor, a chamber containing a body of material controlling the movement of the detent, a gate closing the outlet of said chamber, and means whereby the gate is opened on firing the projectile, substantially as set forth. 120

10. A time fuse for projectiles having exploding means, a detent therefor, a chamber containing a body of granular material controlling the movement of the detent, a gate arranged to slide transversely across the out- 125

let of said chamber, and means holding the gate in position until the projectile is fired, substantially as set forth.

11. A time fuse for projectiles having exploding means, a detent therefor, a chamber containing a body of granular material controlling the movement of the detent, a gate arranged to slide transversely across the outlet of said chamber, and a retaining device arranged to shift its position to release the gate when the projectile is fired, substantially as set forth.

12. A time fuse for projectiles consisting of a casing with a chamber, a gate, a material capable of flowing from the chamber on opening the gate, an exploder, a hammer therefor arranged to move radially under centrifugal action, and a detent for said hammer controlled by said material, substantially as set forth.

13. A time fuse for projectiles provided with an exploder having a hammer arranged to move under centrifugal action, a detent, a retarding medium therefor, a gate for confining said retarding medium, and means for locking said detent and gate until the projectile is fired, substantially as set forth.

14. A time fuse for projectiles provided with an exploder having a hammer arranged to move under centrifugal action, a detent, a retarding medium therefor, a gate for confining said retarding medium arranged to open under centrifugal action, and means for locking said detent and gate until the projectile is fired, substantially as set forth.

15. A time fuse for projectiles provided with an exploder having a hammer arranged to move under centrifugal action, a detent, a spring for actuating the same in one direction, a retarding medium therefor, a gate for confining said retarding medium, and means for locking said detent and gate until the projectile is fired, substantially as set forth.

16. A time fuse for projectiles provided with an exploder having a hammer, a detent for said hammer, means for positively moving the detent in one direction, a retarding medium for regulating its movement in the other direction, and a gate controlling the flow of said medium, the hammer and gate arranged to move under centrifugal action, substantially as set forth.

17. A time fuse for projectiles provided with an exploder having a hammer, a detent for said hammer, means for positively moving the detent in one direction, a retarding medium for regulating its movement in the other direction, a gate controlling the flow of said medium, the hammer and gate arranged to move under centrifugal action, a locking device for holding the detent against the action of the spring, and means for releasing the locking device on firing the projectile, substantially as set forth.

18. A time fuse for projectiles provided

with an exploder having a hammer, a detent for said hammer, means for positively moving the detent in one direction, a retarding medium for regulating its movement in the other direction, a gate controlling the flow of said medium, the hammer and gate arranged to move under centrifugal action, a locking device for holding the detent against the action of the spring, means for locking said gate, and means for releasing the locking device and gate, on the firing of the projectile, substantially as set forth.

19. A time fuse for projectiles provided with an exploder having a hammer, a detent for said hammer, means for positively moving the detent in one direction, a retarding medium for regulating its movement in the other direction, a gate controlling the flow of said medium, the hammer and gate arranged to move under centrifugal action, and a means for locking said detent and said gate arranged to release the same as the projectile is fired, substantially as set forth.

20. A time fuse for projectiles provided with an exploder having a hammer, a detent for said hammer, means for positively moving the detent in one direction, a retarding medium for regulating its movement in the other direction, a gate controlling the flow of said medium, the hammer and gate arranged to move under centrifugal action, a locking device for locking the detent, and a retainer arranged to hold said locking device in position and movable longitudinally by its inertia to a position to release the locking device on firing the projectile, substantially as set forth.

21. A time fuse for projectiles provided with an exploder having a hammer, a detent for said hammer, means for positively moving the detent in one direction, a retarding medium for regulating its movement in the other direction, a gate controlling the flow of said medium, the hammer and gate arranged to move under centrifugal action, a locking device for locking the detent and gate, and a retainer arranged to hold said locking device and gate in position and movable longitudinally by its inertia to a position to release the locking device and gate on firing the projectile, substantially as set forth.

22. The combination in a time fuse for projectiles, of a casing, a radially movable hammer, a chamber, a piston therein having a stem for engaging the hammer, a spring for moving the piston in one direction, and a gate controlling the outlet of said chamber, the parts arranged to permit the gate to be shifted by centrifugal action when the projectile is fired, substantially as set forth.

23. The combination in a time fuse for projectiles, of a casing, a radially movable hammer, a chamber, a piston therein having a stem for engaging the hammer, a spring for

moving the piston in one direction, a lock for locking the piston against the action of the spring, a gate controlling the outlet of said chamber, the parts arranged to permit the 5 gate to be shifted by centrifugal action, and means for automatically displacing the lock when the projectile is fired, substantially as set forth.

24. The combination in a time fuse, of an 13 exploder, a detent, a piston arranged in a chamber containing a displaceable material, a gate adjustable automatically to control the flow of material from the chamber, and a stop device adjustable to control the extent 15 of movement of the gate, substantially as set forth.

25. The combination in a time fuse, of an 23 exploder, a detent, a piston arranged in a chamber containing a displaceable material, a gate controlling the flow of material from the chamber, and a stop device for controlling the movement of the gate and consisting of a rotatable plate having a cam edge, substantially as set forth.

25. 26. The combination in a time fuse for projectiles, of a casing in sections, one adjustable rotatively in respect to the other, an exploder, a detent, a retarding medium controlling the detent, a gate controlling the 33 flow of said material, and a stop device connected with the adjustable section for controlling the extent of movement of the gate, substantially as set forth.

27. The combination in a time fuse for projectiles, of a casing containing a chamber with an anvil therein, a hammer, having a seat for a cap, movable in said chamber to the anvil under centrifugal action, and a chamber for a priming charge communicating with the chamber having an anvil, and provided with a vent, substantially as set forth.

28. The combination in a time fuse for projectiles, of a casing having a transverse recess, an anvil at one end thereof, a hammer sliding in said recess under centrifugal action, and having a chamber for a priming charge and a vent, and a channel in the casing arranged to be closed by the hammer until the latter is moved to the anvil, substantially as set forth.

29. The combination in a time fuse for projectiles, of a hammer, a detent therefor, a piston connected with said detent and movable in a chamber, a block movable in a recess in the wall of said chamber to engage a shoulder of the piston; and a retaining device sliding in a chamber, bearing normally on said block, and with a recess arranged to 60 be carried opposite said block when the retainer is shifted on firing the projectile, substantially as set forth.

30. The combination in a time fuse, of a casing in two sections clamped together to 5 rotate one on the other, means for prevent-

ing such rotation in the reverse direction of rotation of the projectile, means for securing the parts after adjustment, and exploding and timing means within the casing, substantially as set forth.

31. In a time-fuse, the combination of a time-mechanism, a normally restrained firing-bolt, centrifugally-operated means for holding said time-mechanism normally restrained, and means for controlling the movement of the time mechanism when released from engagement with the centrifugally - operated means.

32. In a time-fuse, the combination of a time-mechanism, a firing bolt, and means for holding said time-mechanism normally restrained, said means adapted to be operated by centrifugal force to release the time-mechanism and thereby the firing-bolt.

33. In a fuse, the combination of a fuse 85 casing, a primer, primer exploding means comprising separate members normally locked together and means for releasing said members one from the other at a predetermined time whereby one of said members is 90 free to move and explode the primer.

34. In a shell-fuse, the combination with a normally restrained time - mechanism and firing bolt, and centrifugal means for releasing said time-mechanism and thereby the 95 firing bolt.

35. In a time-fuse, the combination with a suitable casing, of a spring-actuated piston, held normally restrained by means adapted to be released by centrifugal force, and means 100 for controlling the speed of travel of the piston.

36. In a time-fuse, the combination of a spring-actuated time-mechanism, a normally-restrained firing-bolt, and means for holding 105 said time-mechanism normally restrained, said means adapted to be operated by centrifugal force to release the time-mechanism and thereby the firing-bolt.

37. In a time-fuse, the combination of a 110 spring-actuated time-mechanism, a normally-restrained firing-bolt, means for holding said time-mechanism normally restrained, said means adapted to be operated by centrifugal force to release the time-mechanism and 115 thereby the firing-bolt, and means for regulating the speed of travel of said time-mechanism.

38. In a time-fuse, the combination of a time-mechanism, a firing-bolt held normally 120 restrained by said time - mechanism, and means for holding the time-mechanism normally restrained, said means adapted to be operated by centrifugal force to release said time-mechanism and thereby the firing-bolt.

39. In a time-fuse, the combination of a time-mechanism, a firing-bolt, means for temporarily connecting said firing-bolt with said time-mechanism, and means for holding the time - mechanism normally restrained, 130

said means adapted to be operated by centrifugal force to release said time-mechanism and thereby the firing-bolt.

40. In a time-fuse, the combination with a suitable casing, of a spring-actuated piston, held normally restrained by a movable part adapted to be released by centrifugal force, and means for controlling the speed of travel of the piston.
- 10 41. In a time-fuse, the combination with a suitable casing, of a spring-actuated piston, held normally restrained by a movable part, a normally-restrained firing-bolt, said part

being adapted to be operated by centrifugal force, whereby the piston is released to the 15 action of its spring, and thereby the firing-bolt, and means for controlling the speed of travel of the piston.

In testimony whereof we have signed our names to this specification in the presence of 20 two subscribing witnesses.
